UNITED STATES PATENT OFFICE.

FRANK CLIFFORD, OF CARSON CITY, NEVADA.

AUTOMATIC RAILWAY-ALARM.

SPECIFICATION forming part of Letters Patent No. 279,225, dated June 12, 1883.

Application filed June 3, 1882. (No model.)

To all whom it may concern:

Be it known that I, FRANK CLIFFORD, of Carson City, county of Ormsby, State of Nevada, have invented an Improved Automatic 5 Railway-Alarm; and I hereby declare the following to be a full, clear, and exact description thereof.

My invention relates to a novel automatic railway-alarm to be used at crossings; and it 10 consists in a mechanism attached to the locomotive, preferably between the cylinder and the first driver, consisting of a revolving hub provided with peculiar forked arms, which, by coming in contact with posts placed suitably 15 upon the side of the track, are turned to revolve a disk furnished with an eccentric groove, in which a stud upon the end of a pitman connected through intermediate devices with the steam-whistle travels. There is a 20 peculiar hand-connection to operate the whistle and further and minor details of construction, all of which will hereinafter fully appear.

The object of my invention is to prevent accidents at points where roads cross the railway-track, and this I do by sounding an alarm, which, by reason of the operating mechanism, is not dependent upon vigilance of the engineer, but is automatic in its operation.

Referring to the accompanying drawings, Figure 1 is a perspective. Fig. 2 is a side elevation of the device; Fig. 3, a section. Fig. 4 is a detail of the hub. Fig. 5 is a detail of one arm. Fig. 6 is a perspective of the plate 35 *b*; Fig. 7, a plan of bifurcated end of an arm.

Let *A* represent a portion of a railway-track, which is crossed by a road at the point marked *a*. Upon each side of the crossing and upon both sides of the track are upright posts *B*. 40 These are preferably made of cast-iron, with a finished rounded top and an enlarged base, by which they are securely bolted to the bed-piece. Their size and height are to be regulated by circumstances, depending upon the 45 location and construction of the devices hereinafter described.

Let *C* represent a portion of a locomotive, sufficient to show the cylinder and its front driver, or a portion thereof. To the side of the 50 locomotive, between the cylinder and front driver, is fixed upon a short shaft a hub, *D*.

This upon its inner face is cast solid, but upon its outer face is made into quadrants, in each of which is a flange-socket, *d*. (See Fig. 4.)

E represents four arms. Each of these consists of two parts, of the shape shown in Fig. 5, and when the two sections are put together they form an arm having a tapering shank, which fits in the flange-sockets *d*, and a flaring bifurcated end, as shown. These arms 60 project from the hub at right angles.

Plates *b* cover the quadrants, and bolts *c* pass through the plates and through the meeting edges of the parts of the arms, cutting a semicircle in each and through the inner face 65 of the hub, where they are suitably secured. Thus the parts are held together, and the arms firmly secured to the hub. When damaged, they may be readily removed for the substitution of others.

The short shaft upon which the hub *D* is fixed carries a disk, *F*, in the outer face of which is made an elongated elliptical groove, *e*. *G* is a bracket having guides *g*, through which a vertical rod or pitman, *H*, passes, and is 70 adapted to slide up and down therein.

The lower end of the pitman is provided with a stud, *h*, which fits in the eccentric groove *e*, and its upper end is connected by a rod, *I*, with the end of a rod, *J*, which is 75 adapted to open or close the valve operating the steam-whistle.

Against the periphery of the disk *F* is a brake-block, *K*, held to its position by a strong spring, *k*. (See Fig. 2.)

The operation of the device, as far as at present explained, is as follows: As the locomotive approaches the cross-road one of the arms *E*, which extends downward and a little forward, comes in contact with the top of the 90 first post *B*. Its forked end easily straddles the top of the post, and by it is turned a quarter round. This movement turns the disk *F*, with its eccentric groove *e*, and the stud *h* travels to the top of the groove, thus raising pitman *H*, and through its connections opening 95 the valve of the steam-whistle. The brake *K* presents sufficient resistance to prevent the disk from turning any farther when the pressure is relieved. The whistle continues to 100 sound while the locomotive proceeds to the next post, when the next arm is turned by the

post, and the pitman is drawn down to close the valve of the whistle. By these quarter-turns the arms are always brought into position to be affected by the posts.

5 It may sometimes be necessary for the whistle which is connected with the device to be closed or opened by hand. To provide for this I have the following: Upon the inner face of disk F are cast four projections, *m*. These 10 have their faces which are toward the cab straight, while their backs are inclined planes, as shown. To the bracket G is pivoted, at its center, an S-shaped lever, L, to the upper end of which is connected a rod, N, passing back 15 into the cab. The rod is provided with a spring, *n*, to hold the lever forward. The lower end of the lever L is adapted, when its upper end is drawn back, to come in contact with the straight faces of projections *m*, and thus to turn the 20 disk. The projections are so placed and the stroke of the lever so adjusted that a quarter-turn of the disk is accomplished and the next projection brought into position.

Although I have described the alarm device 25 as being located between the cylinder and the front drum, I do not confine it to that position. It may be placed in any suitable location, according to the builder's judgment, and the connecting-rods may be suitably extended or 30 directed.

The dimensions of the device must be regulated by the location and the size of the engine, and all the parts may be so placed as not to interfere with the other machinery.

35 The iron posts B should be of proper height to cause the arms to revolve a quarter-turn.

The lever and connections giving the engineer control of the device may be arranged to suit the position of the alarm mechanism and 40 other machinery.

The whistle which is operated by this device may be a separate one and different in tone from that controlling the train.

Having thus described my invention, what I 45 claim as new, and desire to secure by Letters Patent, is—

1. The posts B upon the sides of a railway-track, as shown, in combination with the arms E, journaled upon the side of the locomotive, 50 disk F, with its eccentric groove *e*, vertically-moving pitman H, with its stud *h*, traveling

in said groove, and devices connecting the said pitman with the steam-whistle of said locomotive, substantially as and for the purpose herein described.

55

2. The posts B upon the sides of a railway-track, as shown, in combination with the arms E, having bifurcated flaring ends, and secured to a central hub, D, upon a shaft journaled upon the side of a locomotive, disk F, with its eccentric groove *e* upon said shaft, sliding pitman H, with its stud *h*, traveling in said groove, and devices connecting said pitman with the steam-whistle of the locomotive, substantially as and for the purpose herein described.

65

3. The posts B upon the sides of a railway-track, as shown, in combination with the forked arms E, consisting each of two parts with flaring outer ends and tapering shanks, the hub D, divided into quadrants upon its outer face, 70 in each of which is a flange-socket, *d*, in which the tapering shanks of the arms E fit, and provided with cover-plates *b* and securing-bolts *c*, for the purpose described, the disk F, with its eccentric groove *e* upon the same shaft as hub 75 D, the sliding pitman H, with its stud *h*, traveling in said groove *e*, and devices connecting said pitman with the steam-whistle of the locomotive, substantially as and for the purpose herein described.

80

4. The posts B, in combination with a hub, D, upon the locomotive, and the series of four arms, E, having flaring bifurcated ends, the disk F, with its elongated elliptical groove *e*, brake-block K, with its spring *k*, pitman H, 85 with the stud *h*, fitting said groove, and devices connecting said pitman with the steam-whistle of the locomotive.

85

5. The posts B, in combination with the hub D, arms E, disk F, with its eccentric groove 90 *e* in its outer face and its projections *m* upon its inner face, pitman H, with its stud *h*, fitting groove *e*, rods J and I, connected with the pitman and with the whistle of the locomotive, and the S-shaped lever L, rod N, and spring 95 *n*, all arranged as and for the purpose herein described.

95

In witness whereof I hereunto set my hand.

FRANK CLIFFORD.
